United States Patent

Des. 234,306
Patented Feb. 11, 1975

234,306

GAME CLUB HEAD

Robert T. Cummings, Long Beach, Calif.
(E. 12 La Crosse, Spokane, Wash. 99207)

Filed Mar. 9, 1973, Ser. No. 335,061

Term of patent 14 years

Int. Cl. D21—02

U.S. Cl. D34—5 CQ

FIG 1

FIG 2

FIG 3

FIG 4

FIG 5

FIG 6

FIG 7

FIG. 1 is a side elevational view of a game club head showing my new design;

FIG. 2 is an end view of the face from either end taken along the line 2—2 in FIG. 1;

FIG. 3 is a top plan view of FIG. 1 taken along the line 3—3 in FIG. 1;

FIG. 4 is a side elevational view of the opposite side of FIG. 1;

FIG. 5 is a sectional view taken along the line 5—5 in FIG. 3;

FIG. 6 is a sectional view taken along the line 6—6 in FIG. 3; and

FIG. 7 is a sectional view taken along the line 7—7 in FIG. 1.

I claim:

The ornamental design for a game club head, as shown and described.
